UNITED STATES PATENT OFFICE.

RUDOLF E. HELLMUND, OF SWISSVALE, PENNSYLVANIA, ASSIGNOR TO WESTINGHOUSE ELECTRIC & MANUFACTURING COMPANY, A CORPORATION OF PENNSYLVANIA.

DYNAMO-ELECTRIC MACHINE.

1,327,821.

Specification of Letters Patent. Patented Jan. 13, 1920.

Application filed December 14, 1916. Serial No. 136,895.

To all whom it may concern:

Be it known that I, RUDOLF E. HELLMUND, a subject of the German Emperor, and a resident of Swissvale, in the county of Allegheny and State of Pennsylvania, have invented a new and useful Improvement in Dynamo - Electric Machines, of which the following is a specification.

My invention relates to dynamo-electric machines and particularly to machines embodying concentric windings.

One object of my invention is to provide a concentric and a main winding for a dynamo-electric machine which will be very compact and may be rigidly braced in position and thoroughly insulated to protect the same against the destructive influences of vibration.

Another object of my invention is to provide an improved form of insulator for a winding of the above-indicated class.

Heretofore, when it has been desired to provide an armature with a main and an auxiliary field winding, it has been necessary to either bring the leads from both sides of the core or to provide special room at one side of the core for the group connectors of the winding, since these connectors were necessarily positioned on the same side of the core as the leads. Furthermore, by reason of the very crowded conditions prevailing, it has been difficult to properly insulate and brace the windings. The coils of such machines were subject to severe vibration which, in many instances, resulted in the breaking down of the insulation and connections.

My invention proposes an improved form of winding in which the group connectors are located on the side of the coil opposite to the main leads. An improved form of insulator, comprising an insulating cap, that is adapted to entirely inclose the end of the bar and to be readily applied to windings of this type, has been devised to facilitate the insulation of machines of this character. An improved form of coil brace, by which each coil is partially supported from adjacent coils, has also been provided to rigidly secure the end connectors in place and prevent the destructive effects of vibration.

Figure 1 of the accompanying drawing is a side elevational view, partially diagram-

matic in form, of a dynamo-electric machine constructed in accordance with my invention; Fig. 2 is a schematic diagram of the improved form of winding shown in Fig. 1; Fig. 3 is a side sectional view of an insulator constructed in accordance with my invention; Fig. 4 is a sectional view on the line 4-4 of Fig. 3; Fig. 5 is a sectional view of a modified form of the insulator shown in Fig. 6 that is adapted to be employed for insulating inductor bars of rectangular cross section; and Fig. 6 is an end view of the insulator shown in Fig. 5.

The dynamo-electric machine shown in Fig. 1 of the drawing comprises a core 1 which is provided with a concentric main winding 2 and a concentric compensating winding 3. The core 1 is provided with a plurality of insulated bars 4 and 5 which comprise the inductors for the windings 2 and 3. The bars 4 are disposed in widely separated groups to provide a concentric winding that is adapted to be used as the main winding, whereas the bars 5 are distributed over the remainder of the pole faces and constitute a compensating winding. Fig. 2 of the drawing shows a schematic diagram of the windings 2 and 3 in which bars 4 are assembled into a plurality of coil groups 6, 7, 8 and 9 by a plurality of end connectors 10. The various groups of bars 4 are connected by group connectors 11. The bars 5 are connected into groups 12 by a plurality of end connectors 13. Group connectors 14 are provided for connecting the coil groups 12. The winding 3 is of a usual form employed in dynamo-electric machines of this type and comprises leads 15 which supply energy to the coil groups 12 through group connectors 14. It will be noted that the leads 15 are on the same side of the core member as the group connectors 14, which is in accordance with customary practice. Leads 16 and 17 supply energy to the main winding 2 through group connectors 11 which are positioned on the side of the core opposite to the leads 16 and 17. The location of the main winding leads 16 and 17 in this favorable position is made possible by employing a single active inductor 18, or an uneven number of inductors, from a coil group 8 as a lead to the adjacent coil group 9. The coil group 8 is thus provided with

terminal leads 16 and 17 and is respectively connected to the adjacent coil groups 7 and 9 by group connectors 11.

Referring particularly to Fig. 1 of the drawing, which is a view of the core 1 taken on the side opposite to that on which the winding leads 15, 16 and 17 are brought out, the connectors 10 on the lead side of the core 1 are shown diagrammatically in order 10 to simplify the drawing. Current for the winding 2 is conducted from the lead 17, through inductors 4 and the corresponding end connectors 10 of the coil group 8, and an improved group connector 11, to the coil 15 group 7. The end connectors 10 are formed from strap copper and are bound together by tape 20. The group connectors 11 severally comprise strap conductors 21 and 22 and a jumper connection 23 which electrically 20 connects the conductors 21 and 22 but is insulated from the interposed end connectors 10. The conductor 22 extends between the jumpers 23 of the coil groups 7 and 8 and an end portion 24 thereof which extends 25 beyond the group 8 to the adjacent group 9 and constitutes a brace to which the coil group 9 is secured by tape 20. The end connectors 13 are positioned close to the core 1 and may be compactly bound together. The 30 bars 4 extend beyond the bars 5 in order that the end connectors 10 may be positioned outside of the end connectors 13.

Insulators 25 are provided to effectively insulate the ends of the bars 5 from the bars 35 4 and the corresponding connectors. Each of the insulators 25 comprises a shield 26 having a laterally-extending sleeve 27 which is adapted to extend longitudinally along the bar 5 and is open at one side to admit the bar 5. A cap 28 is provided which may be placed over the end of the bar 5 after the end connector 13 has been secured thereto and has a portion 29 that is admitted within the sleeve 27 of the disk member 26. 40 A side opening 30 is provided for the connectors 13. The cap member 28 has an end piece 31 that effectively protects the end of the bar 5. Fig. 3 shows a modification of the insulator 25 that is particularly adapted 45 to insulate the ends of the bars 4 which extend beyond the bars 5. The bars 4 are provided with slot insulation 32 over the rectangular portion of the inductor 4. The strap connectors 10 are soldered to the cylindrical end portions of the bars 4, and tape 33 is wound around the conductors intermediate the connectors 10 and the insulation 32. An insulating cap 35, that is composed of a slotted insulating tube and an end 50 piece 36, is adapted to be placed over the end of the conductor and secured in place by tape 37. This provides an effective and easily applied insulating cap for the ends of the bars 4.

65 The winding 2 may be employed with

various forms of auxiliary windings or by itself but the greatest advantage accrues therefrom when it is used in connection with a usual type of winding 3 in which the group connectors are positioned on the same 70 side of the core as the main winding leads. By combining a winding of this latter type with a winding employing group connectors which are positioned on the opposite side of the armature core from the main winding 75 leads, it is possible to secure an even distribution of the end and group connectors for the two windings and, at the same time, to bring the main winding leads out at one side of the armature core without employing auxiliary conductors. This avoids the crowding together of all of the group connectors on one side of the core and provides a winding which may be easily braced and insulated. It will also be noted that the bar 80 insulators are particularly effective for insulating a winding of this type.

Although I have described a particular embodiment of my invention, it is not so limited and I desire that only such limitations shall be imposed as are indicated in the appended claims.

I claim as my invention:

1. In a dynamo-electric machine, the combination with a core, of a winding for said core comprising a plurality of coil groups, a plurality of strap connectors for said groups disposed on one side of said core, each connector being mechanically connected to three coils for rigidly grouping the 100 coils together, and leads for said winding disposed upon the opposite side of said core.

2. In a dynamo-electric machine, the combination with a core, and a concentric winding for said core comprising a plurality of 105 coil groups, of group connectors for electrically connecting said coil groups, and means for extending each connector to mechanically secure each coil group to the adjacent coil groups in order to rigidly support said winding.

3. In a dynamo-electric machine, the combination with a core, and a winding for said core comprising a plurality of bars, of end connectors for grouping said bars into coils, and group connectors for said coils, an electrically inactive end of one of said group connectors extending to an adjacent coil and secured thereto to rigidly connect all of said coils.

4. The combination with a winding comprising a bar conductor, of an insulator for the end of said bar comprising an insulating disk having a laterally-extending sleeve and a cap surrounding the end of said bar and having a portion thereof disposed within said sleeve.

5. The combination with a winding comprising a bar conductor, of an insulator for the end of said bar comprising an insulating

disk having a laterally-extending sleeve, said sleeve and disk having an open side for admitting said bar, and a cap surrounding the end of said bar and having a portion 5 thereof disposed within said sleeve.

6. The combination with a winding comprising a bar conductor, and an end connector for said conductor, of an insulator for the end of said bar comprising a disk 10 slotted to receive said bar, a laterally-extending sleeve secured to said disk and having a side opening to admit said bar, and a cap for incasing the end of said bar and provided with an opening through which 15 said end connector extends.

7. The combination with a winding comprising a bar conductor, and an end connector for said conductor, of an insulator for the end of said bar comprising a disk 20 slotted to receive said bar and having side portions extending longitudinally along said bar, and a cap for incasing the end of said bar and provided with a lateral opening through which said end connector extends 25 and having a portion of said cap extending within the side portions of said disk.

8. In a dynamo-electric machine, a core member, two concentric windings for said core member, each of said windings comprising a plurality of coil groups, connectors 30 for joining the coil groups of each winding, said connectors for the two windings being disposed on the respective sides of the core member, and leads for the two windings which are all located on one side of the core 35 member.

9. In a dynamo-electric machine, a core member, a main and a compensating concentric winding mounted on said core member, each of said windings comprising a 40 plurality of coil groups, two groups of connectors for joining the coil groups of the respective windings, said groups of connectors being located on the respective sides of the core member, and leads for the two 45 windings that are located on the side of the core member that is opposite to the connectors for the main field winding.

In testimony whereof I have hereunto subscribed my name this 7th day of Dec. 50 1916.

RUDOLF E. HELLMUND.
